UNITED STATES PATENT OFFICE.

MARK S. MORSE, OF LOS ANGELES, CALIFORNIA, ASSIGNEE TO MAGNETIC SIGNAL CO.,
A CORPORATION OF CALIFORNIA.

COIL CUT-OUT FOR WIGWAG SIGNALS.

Application filed January 25, 1923. Serial No. 615,423.

To all whom it may concern:

Be it known that I, MARK S. MORSE, a citizen of the United States, residing at Los Angeles, in the county of Los Angeles and State of California, have invented a new and useful Coil Cut-Out for Wigwag Signals, of which the following is a specification.

My invention relates to wigwag signals, 10 that is to say, to signals which are particularly adapted for use at highway crossings of railroads for the purpose of warning traffic on the highway as to the movement of trains on the railroad, such signals being 15 commonly constructed to include a flag or target which is oscillated from one extreme position to another by means of magnets.

The principal object of the invention is to 20 provide means in such a signal for providing a large start-torque so that the signal may be started under adverse conditions as to friction or weather, and also to provide means whereby the operating torque is reduced, after the signal is once started, for 25 the purpose of improving the operation and reducing the power consumption.

Referring to the drawing which is for 30 illustrative purposes only,

Fig. 1 is a diagrammatic section through 35 one form of my invention.

Fig. 2 is a diagram showing the arrangement of one set of magnets and the armature, and,

Fig. 3 is a diagram of connections.

In the form of signal to which I show my invention applied, 11 is a shaft which is journaled in a case 12 and from which a target 13 is suspended by means of a rod 14 which passes through the bottom of the case 12. Supported on arms 15 from the shaft 11 is an armature 20. Secured on one side of the case 12 is magnet 21 and secured to the other side of the case is a magnet 22. The magnet 21 is provided with coils 23 and 24 and the magnet 22 is provided with coils 25 and 26. Also carried in the shaft 11 is a switch blade 30 which makes electrical contact with contacts 31 and 32, for the purpose of alternately energizing the magnets 21 and 22 and thereby alternately attracting the armature 20 to one side and then the other for the purpose of oscillating the signal.

The parts so far described are at the present time well known and in general use, the

structure described being merely selected for the purpose of illustration. In signals of this type which require to be started, sometimes under adverse conditions, it is highly desirable to have a large starting torque so that the signal will be very reliable. The amount of energy required to operate this signal once it is started being considerably less, it is desirable to provide for an excess starting torque to take care of unfavorable starting conditions and to later reduce the power so that economy of current consumption will result, the latter being especially important where the signal is operated from primary parts as is often the case in the application of such signals to practical railway work.

For the purpose of supplying this large starting torque and readily reducing it, I provide a holding magnet 40 having an armature 41, carrying a switch blade 42. The armature 41 is pivoted at 43 and naturally lies in the position shown in Fig. 1 with the blade 42 in its upper position in which position it makes contact with a contact 45. Whenever the armature is closed the blade makes contact with a contact 46. For the purpose of closing the armature I provide a flexible finger 47 carried by the moving structure of the signal, this finger striking against a projection 48 on the armature 41 when the signal makes a full oscillation and forcing the armature into its closed position, in which position the blade 42 makes contact with the contact 46. The method of connecting the above apparatus is as follows:

The coils 23 and 24 are connected at one end through a wire 50 to the contact 31. The coils 25 and 26 are similarly connected by the wire 51 to the contact 32. The other end of the coils 24 and 25 are connected in a pair directly to a wire L¹. The other end of the coils 26 and 23 are similarly connected in a pair and are connected through a wire 54 with the contact 45. The wires L¹ and L² lead from the signal to the external circuit which is so arranged that these wires are energized whenever it is desired to operate the signal. Such external circuit, and the means for energizing it being old and well known in the art need not be illustrated.

The method of operation is as follows: The parts being in the position shown in

Figs. 1 and 3, and the wires L^1 and L^2 being energized, current flows through the switch blade 30 and the wire 50 to the coils 23 and 24 and from these coils through the wire 53 to the wire L^1 , thus energizing the coils 23 and 24 and magnetically energizing the magnet 21. This pulls the armature 20 to the left from the position shown in Fig. 1 which movement disconnects the blade 30 from the contact 31 allowing the signal to swing freely and to oscillate. The contacts 30, 31 and 32 are so arranged that the wires 50 and 51 are then alternately energized as the signal swings. This arrangement being old in the art forms no part of the present invention and need not be herein described.

During the initial movement of the signal, the coils 23 and 24 are fully energized and the coils 25 and 26 are then energized due to the operation of the parts 30, 31 and 32. During this initial movement and during the first few swings of the target 13, the amplitude of the oscillation is not sufficient to cause the finger 47 to strike the projection 48 and the switch blade 42 remains in contact with the contact 45, thus allowing the coils 23 and 26 to be energized. As soon as the target 13 starts to swing actively so that it approaches its extreme position at either end of its stroke, the finger 47 strikes upon the projection 48, forcing the projection 48 upwardly from the position shown in Fig. 1, and forcing the armature 41 against the magnetic circuit 40. Simultaneously, contact is broken between 42 and 45 and established between 42 and 48. Breaking of the contact between 42 and 45 disconnects the coils 26 and 23 from the wire L^1 and connects the coil 60 between the wires L^1 and the wires L^2 . The connecting of the coil 60 enables the magnet 40 to hold the switch member 42 in its disconnecting position, that is to say, in the position in which the coils 23 and 26 are disconnected. The signal continues to operate due to the coils 24 and 25 being energized until the main circuit through the wires L^1 and L^2 is broken, at which time the signal stops swinging. The breaking of the circuit through the wires L^2 and L^1 , which is accomplished outside the signal, also de-energizes the coil 60 and allows the armature 41 to fall back into its original position as shown in Fig. 1 and the signal is ready to again repeat its operation.

It will be seen that during the starting period all of the coils 23, 24, 25 and 26 are in service and that after the signal gets into operation, the coils 23 and 26 are cut out and held out by the coil 60. This gives twice the pull on the armature 20 during the starting period than is exerted on it after it gets started. This allows an adequate starting torque with a low energy consumption for the total operation.

I claim as my invention:

1. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; and means by which said switch is actuated after said armature starts to oscillate.

2. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; and a member carried by said armature and so placed as to actuate said switch whenever said armature approaches an extreme position.

3. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; a holding magnet so placed as to hold said switch in a position to disconnect said portion of said coils when said switch has been moved to said disconnecting position; means for moving said switch from said disconnecting position whenever the remaining coils are de-energized; and means by which said switch is actuated after said armature starts to oscillate.

4. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; a holding magnet so placed as to hold said switch in a position to disconnect said portion of said coils when said switch has been moved to said disconnecting position; means for moving said switch from said disconnecting position whenever the remaining coils are de-energized; and a member carried by said armature and so placed as to actuate said switch whenever said armature approaches an extreme position.

5. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; a holding

- magnet so placed as to hold said switch in a position to disconnect said portion of said coils when said switch has been moved to said disconnecting position; means for de-energizing said holding magnet whenever the main circuit to said signal is interrupted, said switch being so constructed that it moves from said disconnecting position whenever said holding magnet is de-energized; and means by which said switch is actuated after said armature starts to oscillate. 5
6. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; a holding magnet so placed as to hold said switch in a position to disconnect said portion of said coils when said switch has been moved to said disconnecting position; means for de-energizing said holding magnet whenever the main circuit to said signal is interrupted, said switch being so constructed that it moves from said disconnecting position whenever said holding magnet is de-energized; and means by which said switch is actuated after said armature starts to oscillate. 10 45 50 55
- 15 7. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; a holding magnet so placed as to hold said switch in a position to disconnect said portion of said coils when said switch has been moved to said disconnecting position; a contact carried by said switch adapted to close a circuit to said holding coil whenever said switch is moved to said disconnecting position; and means for de-energizing said holding magnet whenever the main circuit to said signal is interrupted, said switch being so constructed that it moves from said disconnecting position whenever said holding magnet is de-energized; and means by which said switch is actuated after said armature starts to oscillate. 20 60 65 70 75
- 25 8. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; a holding magnet so placed as to hold said switch in a position to disconnect said portion of said coils when said switch has been moved to said disconnecting position; a contact carried by said switch adapted to close a circuit to said holding coil whenever said switch is moved to said disconnecting position; and means for de-energizing said holding magnet whenever the main circuit to said signal is interrupted, said switch being so constructed that it moves from said disconnecting position whenever said holding magnet is de-energized; and a member carried by said armature and so placed as to actuate said switch whenever said armature approaches an extreme position. 30 70
- 35 9. In a wigwag signal, the combination of: an armature mounted to oscillate between two extreme positions; magnets so placed as to actuate said armature when magnetically excited; a plurality of coils for magnetically exciting said magnets; a switch for disconnecting a portion of said coils from the electric circuit; a holding magnet so placed as to hold said switch in a position to disconnect said portion of said coils when said switch has been moved to said disconnecting position whenever said holding magnet is de-energized; and a member carried by said armature and so placed as to actuate said switch whenever said armature approaches an extreme position. 40

In testimony whereof, I have hereunto set my hand at Los Angeles, California.

MARK S. MORSE.
